CLAIM

The ornamental design for a fascia tissue treatment device with a matrix of nine treatment elements, as shown and described.

DESCRIPTION

FIG. 1 is a front, top perspective view of a fascia tissue treatment device with a matrix of nine treatment elements; FIG. 2 is a front elevational view of the device thereof; FIG. 3 is a rear elevational view of the device thereof; FIG. 4 is a right-side elevational view of the device thereof; FIG. 5 is a left-side elevational view of the device thereof; FIG. 6 is a top view of the device of thereof; and, FIG. 7 is a bottom view of the device of thereof.

The broken lines shown as dashed lines are for the purpose of illustrating unclaimed structure, and form no part of the claimed design.

1 Claim, 5 Drawing Sheets

Related U.S. Application Data

filed on Apr. 23, 2019, now abandoned, which is a continuation of application No. 14/188,143, filed on Feb. 24, 2014, now Pat. No. 10,322,057.
